UNITED STATES PATENT OFFICE

SYDNEY E. BENDER, OF BROOKLYN, NEW YORK, ASSIGNOR TO BENZE-PERFECTION
SAMPLE CARD CO., INC., OF NEW YORK, N. Y., A CORPORATION OF NEW YORK

SAMPLE CARD

Application filed October 29, 1930. Serial No. 491,910.

This invention relates to an improved form of sample card books in general, and particularly to a color card book for textile material, as for instance yarn, etc.

One of the objects of my invention is the process of producing color card samples of yarn for use in connection with my sample book.

Another object of my invention resides in the provision of a specific color sample made of yarn and adapted to facilitate more readily judging of the future coloring and appearance of goods to be dyed.

Another object of my invention is the provision and arrangement of individual sample carrier cards, color sample supports and color samples and their attachment and union with one another.

A further object of this invention is the provision of a sample card book composed of any desired number of individual sections adapted for receiving and removably holding individual sample carrier cards and so constructed as to facilitate the accommodation of any number of cards or samples and capable of folding up to a compact unit in the form of a book in the direction from the end sections towards the center of the book.

A still further object of my invention resides in the construction of my sample book, which is composed of individual sections of uniform size connected with one another by flexible joints, which latter increase in width in the direction from both ends towards the center, thereby facilitating the folding of the sections to a book form in such a way as to cause the end sections to fold against the second or adjacent sections with their inner surfaces facing one another, the third sections folding with their inner faces against the back surface of the end sections, the fourth sections folding with their inner surfaces against the back surface of the second sections, the fifth sections folding with their

inner surfaces against the back surfaces of the third sections, etc.

Still another object of my invention is the provision in connection with each section of a backing member attached to the inner surface of the base member of each section and between the reinforcing members thereof, and provided with means for facilitating the attachment thereto and removal therefrom of individual sample carriers of my particular construction.

The foregoing and still further objects of my invention will become more fully apparent from the following description and the accompanying drawings, forming a part of my disclosure, but by no means intended to limit me to the actual construction shown, and in which—

Fig. 1 is a plan view of a portion of an open sample card book, composed of a plurality of sections with their inner or sample attaching surfaces exposed.

Fig. 2 is an end or bottom view of Fig. 1.

Fig. 3 illustrates an end view of a book in folded form and composed of an upper three section portion and a lower four section portion.

Fig. 4 illustrates an end view of one of the book sections.

Fig. 5 illustrates a sample support with its rear face exposed and showing the attachment of the sample.

Fig. 6 is a plan view of a preferred form of my sample carrier, and

Fig. 7 is a plan view of a sample carrier card to which is attached a sample support provided with a sample.

Fig. 8 illustrates a partial plan view of a modified form of a book section.

Fig. 9 is a plan view of a modified form of a sample carrier card provided with a sample support and sample of my construction, and

Fig. 10 is a plan view of a number of sample supports illustrating the attachment

thereto of a continuous piece of yarn preparatory to separating it for use as individual units in accordance with my method.

Referring to the drawings, numeral 10 5 denotes a stiff, relatively wide and flat base member made of cardboard or similar material. At both long sides of the base member are arranged two reinforcing members 11, which are relatively narrow and extending 10 beyond the inner face of the base member while being flush with the outer face or back of the latter.

Secured to the inner face of the base member between the two reinforcing members is 15 a backing strip 12 provided with a plurality of slots 13, arranged in pairs, which slots serve for receiving individual color sample carrier cards 14. The latter consist of a slip or tab of stiff paper or similar material having reduced ends 15 adapted to register with and be inserted into slots 13. The width of the slip portion between the reduced ends prevents the displacement of the cards.

Attached to each card is a sample support 25 16 which is shorter in length than the card and to which is attached at its front face a sample of colored yarn 17. The latter consists of a bundle of parallel yarn threads, longer than the sample support, its ends, in 30 the form of tassels extending symmetrically beyond the edges of the support. The extending yarn ends are secured to the support by a single thread 18 looped around them and swung back and crossed at the rear face of 35 the support to which face the attaching thread is secured either by glue or in any other practical manner.

The rear face of the sample support is then 40 symmetrically attached to the carrier card, as clearly seen in Fig. 7, whereby thread 18 is obscured from view with the exception of the two loops 19 engaging the ends of the yarn sample which are visible.

The sample itself has not only an attractive appearance in itself, but facilitates more 45 readily the judging of the future appearance of yarn to be colored according to the sample which fact alone becomes helpful to the one ordering the coloring in that he can observe 50 not only the color effect of the yarn bunched together between the loops 19, but may visualize the effect in spread yarn or single yarn of the ends extending beyond the loops.

The achievement of the foregoing advantages 55 forms part of the objects of my invention, as does the manner or process of accomplishing them.

Referring to Fig. 10 it will be seen that a 60 row of sample supports 16 are uniformly spaced from one another and that a continuous piece of yarn is placed centrally and lengthwise over them. Then the attaching threads are looped about the yarn portions at the shorter edges of the sample supports so 65 that just the loops 19 remain visible, while

the ends of the attaching threads are brought back to the rear face of the supports and crossed and attached thereto in the manner shown in Fig. 5. Thereafter the yarn is separated by cutting it through centrally between the sample supports as indicated by broken lines 20.

The cutting or separating operation releases the yarn and its own resiliency causes the now overhanging free yarn ends to spread in a fan-like manner, as seen at 21. Now the sample supports are attached with their rear faces to individual carrier cards 14 as described above.

My sample card book may be composed of any number of sections. In Figs. 1 and 2 a portion of a book is shown consisting of four section portions, while in Fig. 3 a folded-up book of seven sections is illustrated in a semi-diagrammatical manner. The sections are 80 connected by flexible joints 22, increasing in width from the end sections inwards.

Taking the illustration in Fig. 3 as a typical example, the upper book portion 23 consists of three sections, while the lower book portion 24 comprises four sections. The end sections of the respective book portions are designated at I and I', the second sections II and II', the third sections III and III' and the fourth section of the lower book portion 95 IV. From this figure it will be also observed how the flexible joints between the sections are arranged as to their widths and in which manner the sections of each book portion are folded.

The joints between sections I and II and I' and II' are designated at 25 and 25', respectively. They are the narrowest joints. The joints between sections II and III and II' and III' are marked 26 and 26', respectively, and are wider so as to accommodate three folded-up sections; the joint 27 between sections III' and IV is still wider to accommodate four folded-up sections, while the joint 28 between sections III and IV is widest, as it has to accommodate seven folded-up sections.

The first two sections of each book portion bear with their inner faces against each other and their reinforcing members abut with the extending faces. Sections III and III' rest with their reinforcing members against the backs of sections I and I'', respectively, and section IV bears with its reinforcing member against the back of section II'. Such arrangement provides not only for end reinforcements of each section singly, but for the reinforcement of the book sides when in folded condition, and incidentally the reinforcing members form spacers between the folded-up sections.

In Fig. 7 an individual sample carrier card is illustrated equipped with a sample support provided with a color designation of the sample. It sometimes becomes advantageous to 130

show such color designation or number in a more prominent way as is indicated in the modified structure illustrated in Figs. 8 and 9. Here again a portion of a book section 29 5 is shown consisting of a base member 30, at the longer sides of which are provided reinforcing members 31, between which is attached to the base member a backing 32. The latter is provided with card receiving slots 33, arranged in pairs, and adjacent to each pair of slots an aperture 34 is cut out.

The carrier card 35 in this modification is very similar to that described previously. One of its reduced ends 36, however, is elongated and provided with an identification marking which latter can be observed when the card is inserted with its elongated end through the right hand slot and under aperture or window 34 which it fills. The relatively spacious provisions for markings or names of the color, or any other designations facilitate distinguishing of the sample at a glance, thereby precluding misunderstandings due to erroneous reading of insufficiently clear designations such as shown in Fig. 7.

While I have illustrated and described only one of the many possible modified forms my invention is capable of assuming, be it understood that other modifications and improvements may be incorporated therein without departing from the broad scope of my idea and I therefore reserve for myself the right to make such changes and improvements as may become advisable during the commercialization of my device within the broadest interpretation of the annexed claims:

I claim:

40 1. A color card sample, comprising in combination a carrier in the form of tab, a yarn sample support representing another tab, but shorter than the first mentioned tab secured with its lower face to the upper face of said carrier, a yarn sample attached to and extending with its ends beyond the edges of said support, and means for securing the extending ends of said yarn sample to the latter in the manner indicated.

50 2. A color sample adapted to be removably secured to a sample color card or book, comprising in combination, a carrier member in the form of a tab having reduced ends, a yarn sample support secured to said member and being shorter than the latter, a yarn sample attached to said support and extending with its ends beyond the edges of the latter, but not beyond the reduced ends of said carrier member, and sample securing means 55 looped about the extending ends of said yarn sample and secured to the back of said support.

60 3. A color sample adapted to be removably secured to sample color cards or books, comprising in combination, a carrier member in

the form of a tab having reduced ends, the latter adapted to serve as movement limiting and engaging means for the tab when secured to such sample color cards or books, a yarn sample carrier secured with its back to said carrier member and forming another tab, but shorter in length than said carrier member, a yarn sample attached to said support and being of greater length than the latter, but being shorter than the portion of the carrier member disposed between the latter's reduced ends, said sample extending with its ends evenly beyond the edges of the support, its center portion adhering uniformly to the exposed face of said support, and binding means looped about and engaging the sample at the edges of said support and secured to the back thereof.

4. A color sample adapted to be removably associated with sample color cards or books, comprising in combination, a carrier member in the form of a tab having reduced ends, the latter adapted to engage sample holding provisions arranged with such cards or books, and to limit its movement when thus engaged, a yarn sample carrier secured with its back face to said carrier member and forming another tab shorter in length than said member, a yarn sample attached to said support and comprising a bundle of parallelly arranged threads, the ends of which form tassels which extend beyond the edges of said support, while its middle portion is uniformly arranged over the front face of the support, an attaching thread looped about the yarn sample at the intersections between its middle and end portions, thereby drawing the looped-over points of the yarn together, the portions of the attaching thread not in engagement with the yarn sample secured to the attached back face of said sample support.

5. A color sample adapted to be removably associated with sample color cards or books, comprising in combination, a carrier member in the form of a tab having reduced ends, one of which ends being longer than the other and adapted for receiving identification markings, both reduced ends designed for engaging sample holding provisions arranged with such cards or books and for limiting the movement of the sample while thus engaged, the longer reduced end adapted to register with an opening or window for exposing the markings provided upon that tab end, a yarn sample carrier secured with its back face to said carrier member and forming another tab shorter in length than said member, a yarn sample attached to said support and comprising a bundle of parallelly arranged threads, the ends of which form tassels which extend beyond the edges of said support, while its middle portion is uniformly arranged over the front face of the support, an attaching thread looped about

the yarn sample at the intersections between its middle and end portions, thereby drawing the looped-over points of the yarn together, the portions of the attaching thread not in engagement with the yarn sample secured to the attached back face of said sample support.

In testimony whereof I herewith affix my signature.
